UNITED STATES PATENT OFFICE.

EDWIN E. KRATZ, OF KANSAS CITY, MISSOURI, ASSIGNOR OF ONE-TENTH TO LOUISE A. WEISS, OF KANSAS CITY, MISSOURI.

FOUNTAIN PEN.

Application filed May 8, 1922. Serial No. 559,287.

To all whom it may concern:

Be it known that I, EDWIN E. KRATZ, a citizen of the United States, residing at Kansas City, in the county of Jackson and State of Missouri, have invented certain new and useful Improvements in Fountain Pens; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to self-filling fountain pens and the primary object is to provide an inexpensive, easily operated, filler-tube-operating mechanism.

The invention consists in certain novel parts and combination of parts, which will be clearly referred to hereinafter, reference being had to the accompanying drawings, in which—

Fig. 1 is a vertical, longitudinal, sectional view through a fountain pen case showing my invention partly in elevation and partly in section, the pen-receiving end of the case being shown in elevation.

Fig. 2 is a similar view showing the filler tube collapsed.

Fig. 3 is a detail perspective view of the filler tube operating mechanism.

Fig. 4 is a detail perspective view of the latch and presser bar actuator, and

Fig. 5 is a cross sectional view through the presser bar actuator and the presser bar for causing the collapse of the filler tube.

Referring now to the drawings by numerals of reference:

40 The outer case or shell 1 of the fountain pen which constitutes the penholder, may be of any appropriate construction, the specific details not being a part of my present invention. The casing 1, however, is shown as provided with a longitudinal slot 2 through which the manually controlled part of the actuator may project. The filler tube 3 may be attached to the portion 4 of the pen holder in any well known manner and it may lie within the casing 1 in the usual way. In order to cause a collapse of the tube so that air will be expelled therefrom to permit ink to enter the tube in a manner to be well understood, I provide an actuator

ing mechanism which is the subject matter of my invention.

The actuating mechanism consists of a presser bar 5 formed from a strip bent over at 6 to provide a return or substantially parallel bar 7, which extends back upon the bar 5 in spaced relation thereto, as shown in Fig. 3. The free end of the actuating bar 5 has an upturned lip 8 for the purpose of preventing the end of the bar 5 from cutting the tube.

The downwardly bent portion 6 constitutes a spring connection between the bar 7 and the bar 5. The bar 5 has an upstanding projection 9 integral therewith which may be formed of the same material as the strip, from which the bars 5 and 6 are formed, and the upstanding projection 9 extends through

a slot 10 cut in the bar 7 by stamping out the flanged projections 11 and 12; the ends 13 and 14 of which can be bent over the outer face of the portion of the casing 1 surrounding the slot 2 so that the bar 7 will be held snugly against the inner face of the casing 1, as clearly seen in Figs. 1 and 2. The flanges 13 and 14 in effect rivet or fasten the bar 5 rigid with the casing or shell 1. The portion 12, however, has a forwardly extending lip 15 directed toward the center of the slot 2 and it is adapted to be engaged by a notch 16 on a latch lever or actuator 17, as shown in Fig. 1. The latch lever or actuator 17 is in the form of a channel, the sides 18 and 19 of which straddle the upstanding projection 9 and are pivotally secured thereto by a pivot or rivet 20.

When the parts are normally in position as shown in Fig. 1, the bar portion 7 of the strip will be fastened rigidly to the case and under normal condition, the latch will lie longitudinally of the case 1 so that the notch 16 will engage the lip 15; therefore, the lever 17 will be locked against movement. It will be noted that the length of the lever is slightly less than the length of the slot 2 (see Fig. 1).

When it is desired to collapse the filler tube 3, the latch lever 17 must be disengaged from the lip 15, and the operator will slide the latch longitudinally toward the pen point, the spring connection 6 permitting a slight longitudinal movement of the bar 5 with respect to the bar 7 so that the disengagement of the notch 16 from the lip 15 can

- 2
- be effected. Then the latch lever 17 can be swung to a lateral position, as shown in Fig. 2. The operator may then press upon the latch lever 17 so as to cause the bar 5 to press against the tube to collapse it as shown in Fig. 2. The pressure may then be released. This may be done one or more times so as to have a pumping action on the filler tube 3.
- 10 When the tube 3 has been supplied with ink, the bar 5 may take the position shown in Fig. 1 with the latch lever 17 in such position that the notch 16 will engage the lip 15 when the latch lever will be locked again.
- 15 When the latch lever is thrown down into the position shown in Fig. 1, it will automatically move into engaging position with the lip because the tendency of the spring connection 6 will be to draw the bar 5 longitudinally far enough to cause the notched portion of the latch lever to move into engagement with the lip 15. The end of the latch lever 21 is in the form of a lip which will overlap the lip 15 so that a smooth appearance will be presented to the observer.
- 20 It will be apparent that the device can be readily applied to the pen casing and that it will be effective in accomplishing the result desired.
- 25 What I claim and desire to secure by Letters-Patent is:
1. A filler tube actuator for pens comprising a strip bent intermediate its ends to form two substantially parallel bars, the portion of the strip connecting the two bars having a spring tendency, an upstanding projection on the lower bar extending through a longitudinal slot in the upper bar, the upper bar having means for attachment to a fountain pen shell, a pivoted latch bar on the upstanding projection extending through the slot, and means on the pivoted latch bar for engagement with the means for securing the upper bar to the shell.
2. The combination with a fountain pen shell and a filler tube therein, of a bar normally lying upon the filler tube, a substantially parallel bar spaced from the first named bar and having yielding connection therewith, the second mentioned bar having a slot coinciding with the slot in the shell, an upstanding projection on the first named bar projecting through the slots in the second mentioned bar and in the shell, a pivoted latch lever connected to the upstanding projection, and means on the latch lever for removably fastening it to the edge of the slot in the shell.
3. A filler tube operating device for fountain pens comprising a pair of parallel bars, yieldingly connected together, one of the bars having a projection extending through a slot in the other bar, means on one of the bars for engaging the edge of a slot in the fountain pen shell, said means having a lip, and a latch lever connected to the lower bar and having a notch for engaging the means for connecting the upper bar to the shell of the fountain pen.
4. A fountain pen filler tube actuator comprising two bars resiliently connected together, one of which is provided with a longitudinal slot and in spaced relation to the other bar, an upstanding projection on the other bar extending through the slot in the first named bar, means for connecting the first named bar to the shell of a fountain pen, and a pivoted lever connected to the projection adapted to swing into and out of operative position so that when in one position it will lie longitudinally of the shell and when in operative position it will lie transversely to the shell.
5. A fountain pen filler tube actuator comprising a bar bent over at one end and back upon itself to form a second bar having a spring connection between the two bars, the bars constituting an upper and lower bar, the upper bar having a longitudinal slot therein with upstanding fountain pen shell engaging members to fasten the upper bar rigidly with respect to the fountain pen shell, a projection extending rigidly with the lower bar and projecting through the slot in the upper bar, and a pivoted lever connected to the projection and having movement through the slot in the upper bar.

In testimony whereof I affix my signature.

EDWIN E. KRATZ.
